UNITED STATES PATENT OFFICE.

ROMAINE MACE, OF NEW YORK, N. Y.

DESIGN FOR A CALENDAR.

SPECIFICATION forming part of Design No. 14,582, dated January 29, 1894.

Application filed July 16, 1893. Term of patent 7 years.

To all whom it may concern:

Be it known that I, ROMAINE MACE, a citizen of the United States of America, residing at New York, in the county of New York and State of New York, have invented and produced a new and original Design for Calendars, of which the following is a specification, reference being made therein to the accompanying drawing.

10 This design is intended to be used for a calendar; and it consists in a representation of a vehicle, with horses attached, having panels, as shown, adapted to receive characters indicating the days of the week and month and the name of the month.

I prefer to arrange said design substantially as follows, reference being had to the accompanying drawing, in which A represents the vehicle; B, the top of the vehicle; C, the horses.

20 On one side of the wagon, under the seat, is represented an oval, D, in which appears the day of the month. On the front of the dash-

board is shown the name of the month, E, and the day of the week, F, is shown on the peak or top. At the sides of the design, and in the 25 distance, are represented various accessories, as buildings, signs, foliage, hydrant, &c.; but these are not essential parts of the design, nor are the eyelet-holes in the blinders and hydrant.

30 What I claim as new is—

The design for calendars herein shown and described, consisting of a representation of horses and vehicle, the latter having on the side thereof a panel adapted to receive characters, the dash-board and peak or top each provided with a panel adapted to receive characters.

In testimony whereof I affix my signature in the presence of two witnesses.

ROMAINE MACE.
